UNITED STATES PATENT OFFICE.

ERNEST R. SEWARD, OF MADISON, WISCONSIN, ASSIGNOR TO GISHOLT MACHINE COMPANY, OF MADISON, WISCONSIN, A CORPORATION OF WISCONSIN.

CARRIAGE-CROSS-FEED STOP MECHANISM FOR LATHES.

1,168,683.

Specification of Letters Patent.

Patented Jan. 18, 1916.

Application filed July 28, 1915. Serial No. 42,328.

To all whom it may concern:

Be it known that I, ERNEST R. SEWARD, a citizen of the United States, residing at Madison, in the county of Dane and State 5 of Wisconsin, have invented certain new and useful Improvements in Carriage-Cross-Feed Stop Mechanisms for Lathes, of which the following is a specification.

This invention relates to improvements in 10 lathes of that type employing a carriage cross-feed having both manual and power cross-feed mechanisms; and the principal object of the invention is to provide a new and improved automatic mechanism for arranging 15 the power feed at predetermined points governed by the tools used in the faces of the tool post and the operations to be performed thereby.

In a simple form the invention is applicable 20 to a carriage cross-slide carrying a tool post having a single face; but the principal advantage and utility of the invention is in connection with carriage cross-slides carrying tool posts having a plurality of faces.

Other minor objects and advantages of the 25 invention will be apparent from the following detailed description when considered in connection with the accompanying drawings wherein I have illustrated one practical embodiment of the invention, and in which—

Figure 1 is a front elevation, with parts appearing broken out and in section, of the carriage slide and its apron, the cross slide and tool post mounted thereon, and external 30 parts of my improved stop mechanism; Fig. 2 is a view of the parts shown in Fig. 1 as seen from the right of the latter figure, the tool post appearing in elevation and the underlying parts in vertical section on the 35 line 2—2 of Fig. 1; Fig. 3 is a horizontal section on the line 3—3 of Fig. 2; Fig. 4 is a top plan view of certain parts of the automatic stop mechanism, looking downwardly on the line 4—4 of Fig. 1; Fig. 5 is an enlarged detail view, partly in section on the 40 line 5—5 of Fig. 1; Figs. 6 and 7 are detail views illustrating parts of a manually operable clutch shifting device and means for locking the clutch in either of two working 45 positions or in neutral position.

Referring to the drawings, 1 designates a portion of the lathe-bed on which are formed the usual inverted V-ways 2, and 3 designates the carriage slide mounted on the 50 ways 2 and carrying the cross slide 4, this

latter in turn having mounted thereon the usual tool post 5.

6 designates the carriage apron bolted to and depending from the carriage 3 and carrying suitable bearings for lead screws 7 60 and 8 and quick traverse shaft 9.

The cross slide 4 carries non-revolving screw 10 that is held from rotation by a key 11. On screw 10 is a cross feed nut 12 that is secured by a key 13 to a sleeve 14 journaled at 15 in the cross slide 4. On the sleeve 14 is formed a wide pinion 16, and on its outer end is secured a hand wheel 17. Loosely mounted on the outer end of sleeve 14, just inwardly of the hand wheel 17 is a 70 bracket 18 carrying a flat bar 19 which is held from endwise movement by a set screw 20. When it is desired to feed the tool post 5 in or out by hand, the hand-wheel 17 is revolved in either direction, and the rotation 75 of nut 12 on the non-revolving screw 10 imparts the desired motion to the tool post 5.

Referring now to the power feed mechanism, engaging with the wide pinion 16 is an idler gear 21 loosely mounted in the 80 apron on a stud 22 and driven by a pinion 23 secured to or formed on the inner end of a long externally threaded sleeve 24. Loosely mounted on the hub of pinion 23 is a gear 25 that has a friction clutch connection to the sleeve 24 by means of friction ring 26 on the gear 25, a friction ring 27 splined to the sleeve 24 and an interposed split friction ring 28 that is adapted to be expanded to clutch the rings 26 and 27 together by means of a tapered pin 29 mounted in the member 27 and forced outwardly by a rod 30 slidably mounted in the sleeve 24 and having a cam end 31 engaging the inner cam end 32 of the pin 29. By the means 90 last described the gear 25 is normally locked to the sleeve 24 carrying the pinion 23. Gear 25 is driven from a pinion 33 fixedly secured on the hub of a bevel gear 34, which latter, as best shown in Fig. 3, is rotated 100 from a power driven shaft 35 through a double faced clutch 36 splined on shaft 35 and adapted to be coupled to either of a pair of oppositely facing bevel pinions 37 and 38 both loosely mounted on shaft 35 and meshing with pinion 34. Since the shaft 35 runs constantly in one direction, motion in either direction is imparted through the described gear train to the cross feed nut 12, depending upon the direction in which the clutch 105

36 is shifted. This clutch 36 is manually controlled by the operator through a handle sleeve 39 that is slidably but non-rotatably mounted by means of a key 40 and slot 41 on a shaft 42 that carries at its inner end an eccentric pin 43 engaging the annular groove 36' of the clutch 36. The shaft 42 is mounted in a sleeve 44, which latter in turn is non-rotatably mounted, by means of 5 a set screw 45, Fig. 2, in the hub of a supporting bracket 46 that is pivotally supported so as to be capable of oscillation on the power driven shaft 35. The handle sleeve 39 is formed with two diametrically opposite square teeth 47 that are adapted to engage either of two pairs of notches 48 and 49 formed ninety (90°) degrees apart in the outer end of sleeve 44. The handle sleeve 39 is normally urged inwardly by a 10 coil spring 50 abutting at one end against the bottom of a socket 51 formed in the handle sleeve and at its outer end against a nut 52 on the outer end of the shaft 42. It will thus be seen that by pulling out the handle sleeve 39 and giving it a quarter turn from 15 neutral position represented by the notches 49, either of the two reversed feeds can be obtained. If it is not desired to operate the power feed, the handle sleeve can be engaged with the notches 49 which throws the clutch 36 to intermediate or neutral position. On the outer end of the pivoted bracket 46 is a laterally projecting lug 53 in which is 20 mounted a catch block 54 that cooperates 25 with another catch block, hereinafter described, to normally hold the bracket 46 in elevated position and with the separable gears 33 and 25 in mesh with each other.

55 designates a bonnet that is bolted to 25 the apron 6, and carries the power feed mechanism, and pivoted on a stud 56 projecting from said bonnet is a bell crank lever, the substantially horizontal arm 57 of which is of considerable width, as shown 30 in Fig. 4, and has on its opposite sides upstanding walls or flanges 58 in which are journaled several threaded rods 59 (four as herein shown), on which rods are mounted a corresponding number of trip blocks 60, respectively. These trip blocks are adjustable lengthwise of their respective rods by 35 screw heads 61 on the outer ends of said rods. The depending arm 62 of said lever carries a catch block 63 forming an element of the catch mechanism that supports the bracket 46 and directly cooperating with the catch block 54. The arm 57 is normally maintained elevated and the catch blocks 54 and 63 are normally maintained 40 in engagement with each other by means of a spring-pressed pin 64 that engages the outer side of the lower end of the lever arm 62.

The bonnet 55 is formed with a hollow hub 65 that, as shown in Fig. 1, has a wide

longitudinal slot 66 in its lower side. Fitted into the outer end of the hub 65 is a bearing block 67 that supports the outer end of the threaded hollow shaft or sleeve 24; and threaded into the outer end of said sleeve 24 is a screw 68 by which the clutch locking rod 30 is actuated endwise by a screw driver applied to the outer end of screw 68. Mounted on the hub 65 is a sleeve 69 having in its lower side a relatively narrow longitudinal slot 70. Mounted on the threaded sleeve 24 is a traveler nut 71, to the lower side of which is secured a trip dog 72 that projects through both the slots 66 and 70 and is traversed lengthwise of the threaded sleeve 24 by the rotation of the latter, the traveler nut and dog being confined against rotation by the sides of the slot 70. The trip dog 72 is designed to co-operate with any one of the four trip blocks 5 60 to effect the release of the catch mechanism, depending upon the angular position of the sleeve 69 relatively to its supporting hub 65. Adjustment of said sleeve 69 is effected by the means shown in Figs. 1 and 5, and consists of a spring-pressed plunger 73 mounted in a lateral lug 74 carried by the sleeve 69, said plunger co-operating with any one of a series of holes 75 formed in a stationary segment plate 76 rigid with the bonnet 55. When the spring plunger 73 is engaged with the upper hole 75, the trip dog 72 will be swung laterally to a position wherein it will not engage any of the adjustable trip blocks 60; but when said plunger is engaged with any one of the other four holes 75, the trip dog 72 will engage with one of the trip blocks 60 and trip the feed at a point determined by the operator when he adjusts the screws 59. In the instance shown four adjustable screws 59 are provided to correspond with four faces of the tool post 5, and when the tool post is manually operated to bring one of the four faces into proper relation with the chuck, the operator also manually sets the sleeve 69 by pulling out the spring plunger and engaging it in the location corresponding to the selected tool post face.

77 designates a collar secured on the outer end of threaded sleeve 24 confining the latter against endwise movement inwardly.

It may here be noted that the friction clutch 26, 27 and 28 serves merely as a safety device to prevent, through slippage, breakage of parts from any abnormal strain that may be brought to bear on parts driven through the described power feed.

From the foregoing description it will be seen that when it is desired to engage the power cross feed, the operator lifts up on the handle 39 after he has engaged the clutch 36 with one of the bevel pinions 37, 38, to give the feed the proper direction, and this upward movement of the handle en-

gages catch block 54 with catch block 63 and brings gear 33 into mesh with gear 25. The proper stop having been selected as already described, according to the particular face of the tool post which is to be moved toward the chuck, and the coöperating trip block 60 having been adjusted according to the predetermined length of the cross feed, the dog 72 travels slowly toward the trip block 60, and when it strikes the latter it depresses the lever arm 57, swings the lever arm 62 outwardly, draws the catch block 63 out of supporting engagement with catch block 54, and allows the handle 39 and the oscillating frame 46 to drop, as indicated by dotted lines in Fig. 2, thus disengaging gear 23 from gear 25 and arresting the power feed. It may here be noted that the pitch of the thread on sleeve shaft 24 is much finer than the pitch of the thread on feed screw 10, being preferably approximately one-fourth the pitch of the latter so that while the cross slide is traveling say twelve inches the trip dog 72 will travel only four inches. Of course, any desired ratio of the pitches of the two screws may be employed as desired. It may further be noted that as the nut 71 always travels in the same direction as the cross slide, and the trip blocks 60 are beveled on both sides, the said nut will trip the feed when the cross slide is feeding out from the center of the machine as well as when feeding in toward the center.

To those skilled in the art it will be apparent that the mechanism herein illustrated and described for performing the functions and accomplishing the purposes of the invention may be variously modified in matters of detail without involving any change of principle, and hence I reserve all such variations and modifications as fairly fall within the terms and spirit of the appended claims.

I claim:

1. In a lathe, the combination of a cross slide, a screw feed therefor, a driven shaft, a gear train, including a pair of separable gears, intermediate said shaft and screw feed, a catch mechanism normally holding said separable gears in mesh, and a trip mechanism for releasing said catch mechanism and including an adjustable trip block, a trip dog coöperating with said trip block to release said catch mechanism, and mechanism for causing said trip dog to travel toward said trip block at a reduced speed relatively to the speed of said cross slide screw feed.

2. In a lathe, the combination of a cross slide, a screw feed therefor, a driven shaft, a gear train, including a pair of separable gears, intermediate said shaft and screw feed, a catch mechanism normally holding said separable gears in mesh, and a trip mechanism for releasing said catch mecha-

nism and including an adjustable trip block, a revolving threaded shaft driven by a member of said gear train, a traveler nut on said threaded shaft, means holding said nut against rotation, and a trip dog carried by said nut and coöperating with said trip block to release said catch mechanism.

3. In a lathe, the combination of a cross slide, a screw feed therefor, a driven shaft, a gear train, including a pair of separable gears, intermediate said shaft and screw feed, a pivoted bracket carrying one of said separable gears, a catch member carried by said bracket, a lever, one arm of which carries a coöperating catch member serving to hold said bracket raised and said separable gears in mesh, an adjustable trip block carried by the other arm of said lever, a trip dog coöperating with said trip block to rock said lever and separate said catch members, and mechanism for causing said trip dog to travel toward said trip block at a speed bearing a fixed ratio to the speed of said cross slide screw feed.

4. In a lathe, the combination of a cross slide, a screw feed therefor, a driven shaft, a gear train, including a pair of separable gears, intermediate said shaft and screw feed, a pivoted bracket carrying one of said separable gears, a catch member carried by said bracket, a lever, one arm of which carries a coöperating catch member serving to hold said bracket raised and said separable gears in mesh, an adjustable trip block carried by the other arm of said lever, a revolving threaded shaft driven by a member of said gear train, a traveler nut on said threaded shaft, means holding said nut against rotation, and a trip dog carried by said nut and coöperating with said trip block to rock said lever and separate said catch members.

5. In a lathe, the combination of a cross slide, a screw feed therefor, a driven shaft, a gear train, including a pair of separable gears, intermediate said shaft and screw feed, a catch mechanism normally holding said separable gears in mesh, and trip mechanism for releasing said catch mechanism and including a plurality of independently adjustable trip blocks, a trip dog, and selective means for causing said dog to engage any one of said blocks whereby to release said catch mechanism.

6. In a lathe, the combination of a cross slide, a screw feed therefor, a driven shaft, a gear train, including a pair of separable gears, intermediate said shaft and screw feed, a catch mechanism normally holding said separable gears in mesh, and trip mechanism for releasing said catch mechanism and including a plurality of independently adjustable trip blocks arranged side by side, a trip dog, means for shifting said dog laterally into line with any one of said blocks,

and means for effecting a travel of said dog toward said block at a speed bearing a fixed ratio to the speed of said cross slide screw feed.

5. 7. In a lathe, the combination of a cross slide, a screw feed therefor, a driven shaft, a gear train, including a pair of separable gears, intermediate said shaft and screw feed, a pivoted bracket carrying one of said separable gears, a catch member carried by said bracket, a lever, one arm of which carries a coöperating catch member serving to hold said bracket raised and said separable gears in mesh, a plurality of independently adjustable trip blocks mounted side by side on the other arm of said lever, a trip dog, means for shifting said dog laterally into line with any one of said blocks, and means for effecting a travel of said dog toward said block at a speed bearing a fixed ratio to the speed of said cross slide screw feed.

8. In a lathe, the combination of a cross slide, a screw feed therefor, a driven shaft, a gear train, including a pair of separable gears, intermediate said shaft and screw feed, a catch mechanism normally holding said separable gears in mesh, and a trip mechanism for releasing said catch mechanism and including a plurality of independently adjustable trip blocks arranged side by side, a revolving threaded shaft driven by a member of said gear train, a traveler nut on said threaded shaft, means for holding said nut against rotation, a trip dog carried by said nut, and means for shifting said dog laterally into line with any selected trip block.

9. In a lathe, the combination of a cross slide, a screw feed therefor, a driven shaft, a gear train, including a pair of separable gears, intermediate said shaft and screw feed, a pivoted bracket carrying one of said separable gears, a catch member carried by said bracket, a lever, one arm of which carries a coöperating catch member serving to hold said bracket raised and said separable gears in mesh, a plurality of independently adjustable trip blocks mounted side by side on the other arm of said lever, a revolving threaded shaft driven by a member of said gear train, a traveler nut on said threaded shaft, means for confining said nut against rotation, a trip dog carried by said nut, and means for shifting said dog laterally into line with any selected trip block.

10. In a lathe, the combination of a cross slide, a screw feed therefor, a power driven shaft, a reversible gear train, including a pair of separable gears, intermediate said shaft and screw feed, a pivoted bracket carrying one of said separable gears, a catch mechanism normally maintaining said bracket raised and said separable gears in mesh, a trip mechanism for releasing said catch mechanism operating in timed relation to the travel of said cross slide, a handle on said bracket for manually restoring the continuity of said gear train and reengaging the parts of said catch mechanism, and direction-reversing mechanism for said gear train associated with and operated by said handle.

ERNEST R. SEWARD.
